PROTECTIVE GARMENT FOR DIVERS

Eugenio Wolk, Venice, Italy, assignor to Pirelli
Società Per Azioni, Milan, Italy

Application February 17, 1948, Serial No. 8,904
In Italy, January 17, 1946

Section 1, Public Law 690, August 8, 1946
Patent expires January 17, 1966

7 Claims. (Cl. 2—2.1)

1

This invention relates to improvements in protective garments for underwater divers and more particularly has reference to such garments made of light sheet rubber or similar elastic material and means for rendering the openings of said garments watertight for underwater wear.

In the prior art, protective garments for underwater operations, such as rescues, explorations and fishing, have generally been made of heavy rubber fabric of such weight and composition as to be more or less stiff and inflexible. Such garments had two serious disadvantages, one of which is that they more or less hindered the free movements of the diver, and the other is that they formed stiff folds, because the garment did not conform closely to the contours of the body. These folds, stiffened by water pressure, often pinched very painfully into the flesh of the diver.

An object of this invention is to provide a garment which avoids these disadvantages by employing a light, soft and flexible sheet rubber or similar elastic material which clings to the contours of the body, without forming stiff folds, and affords the diver maximum freedom of movement and comfort. It also permits the diver to wear underneath the garment a thick woolen undersuit to prevent undue loss of body heat in cold water.

Another object of this invention is to provide means for preventing the entrance of water into the garment when submerged and especially through the joint between the coat and pants of said garment.

With these and other objects in view which may be incident to my improvements, my invention consists of the combination and arrangement of elements hereinafter described and illustrated in the accompanying drawings, in which:

Fig. 1 shows in front elevation the coat of my improved protective garment for underwater divers;

Fig. 2 shows in front elevation the pants of my improved protective garment for underwater divers;

Figs. 3 and 4 show, partly in front elevation and partly in central vertical section, my novel means of assembling the coat and pants in watertight relationship when worn by the diver;

Fig. 4a is an enlarged fragmentary view of the section through the folded garment and belt portion shown in Fig. 4;

Fig. 5 shows, in front elevation, the completely assembled garment for underwater operations;

Fig. 6 is a perspective view of the inner belt of my improved garment; and

Fig. 7 is a similar view of the outer belt for same.

Referring to the drawings, and particularly to Figs. 1 and 2, it will be noted that my improved garment consists of two principal pieces, a coat or blouse 1, and a pair of pants 2, each provided with elongated trunk portions 3 and 4, to permit of an extensive overlap over the central portion of the body. The coat 1 is provided with a collar 5 and sleeves 6, integrally attached thereto. Each sleeve carries an integrally attached cuff 6a. These cuffs and the collar are made of very thin and highly elastic rubber sheet of such size as to permit the insertion of the hands and head therethrough by stretching. The tension in the cuffs and collar is such as to cause them to cling and adhere closely to the wrists and neck, thereby insuring a watertight fit. Moreover, the flexibility of the cuffs and collar is such as to cause a tighter fit with increasing external water pressure. The pants 2 are provided at their lower extremities with integrally attached shoes 7. The coat and pants are made in various sizes to closely fit the body and their elasticity is such that when donned they closely adhere to the body contours.

One of the most difficult problems in connection with two-piece underwater diver's garments is to prevent the entrance of water by seepage through the joint around the waist between the coat and pants. I have solved this problem by joining the coat and pants together by a novel system of multiple overlapping folds of the waist ends of said coat and pants, in the manner shown in Figs. 3 and 4. By reference to Fig. 3, it will be seen that the skirt 3 of the coat 1 is drawn up on the outside of the coat and then folded down over the upper end of the pants, so as to form a U-shaped fold 8 enclosing the upper edge of the pants 2. The fold 8 is then bent down over its outer edge so as to form a U-shaped fold 9 in the upper end of pants 2, interlocking with U-shaped fold 8 in the manner shown in Fig. 4a. Fold 9 not only interlocks with the fold 8, but also embraces it, forming an integral cincture 10 around the waist of the diver, as shown in Fig. 5. Because of the elasticity of the sheet rubber or similar elastic material of the coat and pants, the cincture 10 closely embraces the body of the

diver and holds the interlocking folds 8 and 9 so tightly together as to normally prevent the seepage of water therethrough.

In order to provide against seepage of water between the coat and pants in the event of an accidental disarrangement of the folds 8 and 9 from some unusual exertion of the diver, I have provided a novel scheme of two interlocking belts, as illustrated in Figs. 6 and 7. The inner belt 11 (Fig. 6) is composed of a thick band of soft rubber 12 having formed in its outer face a concave groove 13 and is reinforced on its inner face by a closely adhering, thin, flexible steel band 14, which projects beyond one end of rubber band 12, forming a tongue 15, adapted to be inserted into a plurality of keepers 16, integrally attached to the inner face of the other end of the steel band 14. The rubber band 12 has squared ends 17 adapted to closely abut each other, when belt 11 is drawn up tightly by outer belt 18, so as to leave no gap between said ends 17.

The outer belt 18 is formed of a flexible and somewhat elastic rope, adapted to be held tightly around the waist of the diver by a traction buckle 19.

Belts 11 and 18 are applied in donned position as follows. After the first U-shaped fold 8 is made in coat 1, as indicated above (Fig. 3), the inner belt 11 is put on over the trunk 4 of pants 2, just below the fold 8, as indicated in Fig. 3 and then slipped up on trunk 4 until it abuts snugly against the lower, outer edge of the fold 8. The fold 8 is then folded down over the belt 11, to form the fold 9, as described above and shown in Fig. 4, thereby tightly embracing the belt 11 between the folds 8 and 9. The outer belt 18 is then applied around the diver's waist over the middle of inner belt 11 (and fold 9) and is made tight by buckle 19. When in this position, the convex surface of belt 18 deforms the flexible fold 9 into the concave groove 13 of inner belt 11. This indentured contact not only serves to hold the belt 18 firmly in fixed position, but by pressing the fold 9 into concave groove 13 of the belt 11, forms a fluted, water-tight joint between the coat 1 and the pants 2, at all times, even when the diver is engaged in heavy exertion.

While I have shown and described the preferred embodiment of my invention, I desire it to be understood that I do not limit myself to the precise details of construction shown by way of illustration, as these may be changed and modified in combination and arrangement by those skilled in the art without departing from the spirit of my invention or exceeding the scope of the appended claims.

I claim:

1. A two-piece protective garment for underwater diving comprising a separate coat and pants with shoes integrally attached, both coat and pants made of elastic and waterproof material adapted to closely embrace the diver's body, said coat having integrally attached annular col-

lar and cuffs of relatively thinner and more elastic material, also adapted to closely embrace the diver's neck and wrists and to increase such embracement with increase of external water pressure.

2. A garment according to claim 1, wherein the coat and pants each have waist portions extended to such lengths as to permit multiple overlying folds.

10 3. A two-piece protective garment for underwater diving comprising a separate coat and pants of elastic and waterproof material adapted to closely embrace the diver's body and, joined together by multiple overlying folds of adjacent 15 ends of each, thereby forming a watertight joint between said coat and pants.

4. A two-piece protective garment for underwater diving comprising a separate coat and pants of elastic and waterproof material adapted to closely embrace the diver's body and, joined together by multiple interlocking folds of adjacent portions of each, thereby forming a watertight joint between said coat and pants.

5. A multiple-piece protective garment for underwater diving comprising a separate coat, pants and belt, all made of elastic and waterproof material adapted to closely embrace the diver's body, said coat and pants being joined together by multiple interlocking folds of adjacent portions of each, said folds being held in intimate contact by the elastic tension of said belt and thereby forming a watertight joint between said coat and pants.

6. A garment according to claim 5 wherein the belt consists of an inner and an outer band, adapted to elastically embrace the folds of the coat and pants between said bands in a compressed and indentured contact with each other, thereby preventing accidental separation of said folds from each other.

7. In an underwater protective garment, a waist belt comprising an inner and an outer band, said outer band being composed of elastic material, said inner band being composed of soft resilient material, reinforced by a flexible metal liner and having a concave groove in its outer face, adapted to form a seat for said outer band and thereby hold in the elastic embrace of said outer band adjacent portions of said garment inserted between said bands in an indentured, watertight contact with each other.
